UNITED STATES PATENT OFFICE.

GILBERT L. CROWELL, JR., OF ARLINGTON, NEW JERSEY.

DESIGN FOR A HANDLE FOR SPOONS, FORKS, OR SIMILAR ARTICLES.

No. 37,562.

Specification for Design.

Patented Sept. 26, 1905.

Application filed August 7, 1905. Serial No. 273,195. Term of patent 7 years.

To all whom it may concern:

Be it known that I, GILBERT L. CROWELL, Jr., a citizen of the United States, residing at Arlington, in the county of Hudson and State of New Jersey, have invented a certain new, original, and ornamental Design for Handles for Spoons, Forks, or other Similar Articles, of which the following is a specification, reference being had to the accompanying drawings, forming a part of the same.

Figure 1 is a front view of a handle for a

spoon, fork, or similar article, showing my new design. Fig. 2 is a reverse view of the same.

I claim—

The ornamental design for a handle for a spoon, fork or similar article, as shown.

GILBERT L. CROWELL, JR.
